UNITED STATES PATENT OFFICE.

HENRY SIEBEN, OF KANSAS CITY, MISSOURI.

DESIGN FOR AN ELECTRIC HEATER.

Application filed June 13, 1921. Serial No. 477,279. Term of patent 3½ years.

To all whom it may concern:

Be it known that I, HENRY SIEBEN, a citizen of the United States, residing at Kansas City, in the county of Jackson and State of Missouri, have invented a new, original, and ornamental Design for Electric Heaters, of which the following is a specification, reference being had to the accompanying drawing, forming part thereof.

In the drawing:

Figure 1 is a face view of an electric heater, showing my new design.

Figure 2 is a rear view of the same.

Figure 3 is a side elevation of the same.

I claim:

The ornamental design for an electric heater, as shown.

HENRY SIEBEN.
